FILLING NOZZLE ASSEMBLY

Norman E. Craw, Chehalis, Wash.

Application February 10, 1956, Serial No. 564,670

3 Claims. (Cl. 141—360)

This invention relates generally to attachments for filler cans and is more particularly concerned with a novel nozzle assembly including valve means for preventing loss of liquid when a filler can such as a brake fluid can, for example, is inverted, and including means for actuating the valve means of the novel assembly when an end portion of the nozzle assembly is inserted into a filler aperture into which the liquid is to be poured.

A further object of invention in conformance with that set forth above is to provide a nozzle assembly of the character set forth including means for retaining the valve means of the novel assembly in resiliently urged sealing relationship in the nozzle assembly for preventing accidental loss of liquid from the filler can as well as preventing loss through evaporation, for example.

Another object of invention in conformance with that set forth above is to provide a nozzle assembly of the character set forth which is readily and economically manufactured, easily used, and highly practical and efficient for the purpose intended.

These together with other objects and advantages which will become subsequently apparent reside in the details of construction and operation as more fully hereinafter described and claimed, reference being had to the accompanying drawing forming a part hereof, wherein like numerals refer to like parts throughout and in which:

Figure 1 is a perspective view showing the novel nozzle assembly in an inverted position as attached to a fragmentary portion of a filler can;

Figure 2 is a top plan view of the novel nozzle assembly of Figure 1; and

Figure 3 is an enlarged sectional view taken substantially on line 2—2 of Figure 1 showing in phantom lines the alternate position to which the nozzle assembly is moved for the purpose of permitting liquid to be poured from the filler can, and also showing a fragmentary sectional portion of the aperture of a brake master cylinder into which liquid of the filler can is being poured.

Referring to the drawings, the fragmentary portion of a filler can is indicated generally at 10, said filler can incorporating an upper end portion 12 which includes an annular threaded outlet portion 14.

The novel nozzle assembly is indicated generally at 16 and includes a tubular nozzle or body member 18 having secured at its one end by means of welds 20, for example, an annular cap element 22 which is internally threaded at 24 for disposition on portion 14 of the filler can. The cap element 22 includes a central apertured portion 26 which is in communication with the internal bore portion 28 of the nozzle member 18. The intersection of the aperture portion 26 and the internal bore portion 28 constitutes a valve seat portion of the nozzle assembly. Disposed within the cap element 22 adjacent the inner surface portion 30 thereof is a sealing washer element 32 which is sealingly engaged by a lateral annular flange portion 34 of portion 14 of the filler can, the said washer element having a central aperture portion 36 constituting a continuation of the valve seat portion previ-

2

ously mentioned, said valve seat portions being sealingly engaged by a tapered valve element 38 which is centrally apertured at 40 for a purpose to subsequently be described. The valve element 38 may be comprised of any suitable material, such as rubber, cork, or plastic, the same being indicated as being a rubber material in the drawing.

Extending through the nozzle member 18 is a valve element actuating rod 42 which has one end portion 44 thereof extending through the bore portion 40 of the valve element 38 and being suitably secured thereto by means of an enlarged end portion 46 thereof.

The body or nozzle member 18 includes in the end portion 48 thereof a notched-out or cutaway portion 50, and the actuating rod 42 includes an angulated end portion 51 terminating in a laterally extending end portion 52 disposed beyond and reciprocably received in the cutout or notch portion 50 of the nozzle member, said portion 52 continuing as an angularly turned portion 54, substantially parallel to the principal portion 42 of the actuating rod, said portion 54 continuing as an angularly turned portion 56 extending away from the actuating rod 42 in the same direction as portion 52.

The cap element includes an annular flange portion 58 extending beyond the inner periphery of the nozzle member 18 providing a lateral abutment about the apertured portion 26. Extending from an intermediate portion of the actuating rod 42, see Figure 3, is a laterally extending abutment washer or element 62 being secured thereon in any suitable manner, said abutments 58 and 62 constituting longitudinally spaced laterally extending abutment elements, and circumscribed on the actuating rod 42 is a compression spring element 64 which has its opposite ends extending between the aforementioned abutments 58 and 62 whereby said compression spring is effective to urge the valve element 38 into sealing relationship with the previously mentioned valve seat portions.

The fragmentary portion of a hydraulic brake master cylinder is indicated at 66, said fragmentary portion including the usual filler aperture portion 68, and when it is desired to replenish the supply of brake fluid, for example, in said master cylinder the end 48 of the nozzle member 18 is inserted therein, and continued downward movement as illustrated by the phantom lines in Figure 3, results in the portion 56 of the actuating rod 42 engaging the upper surface portion 70 of the master cylinder whereby downward movement overcomes the pressure of the compression spring 64 urging the valve element 38 upwardly, or retaining it in a fixed position wherein the filler can moves downwardly whereafter the brake fluid liquid may be permitted to flow into the master cylinder, upward movement of the filler can 10 immediately results in the removal of pressure on the actuating rod 42 whereafter the compression spring 64 is again effective to prevent flow of liquid from the filler can.

Included in the end portion 48 of the nozzle member 18 is a second notch portion 72 which is of a substantially shorter length than the previously mentioned notch cutout portion 50 of the nozzle member, and when it is desired to positively seal the filler can the actuating rod 42 is rotated with the portion 52 thereof being placed in engagement with the notch 72 resulting in the valve element 38 being resiliently and positively urged into engagement with the previously mentioned valve seat portion.

Thus there has been disclosed a novel nozzle assembly which fully conforms with the objects of invention herefore set forth.

Various positional directional terms such as "upper," "lower," "outer," etc., are utilized herein to have only a relative connotation to aid in describing the device and it is not intended to require any particular orientation with respect to any external elements.

The foregoing is considered as illustrative only of the principals of the invention. Further, since numerous modifications and changes will readily occur to those skilled in the art, it is not desired to limit the invention to the exact construction and operation shown and described, and accordingly all suitable modifications and equivalents may be resorted to, falling within the scope of the appended claims.

What is claimed as new is as follows:

1. A nozzle assembly for filler cans comprising a tubular elongated nozzle member, a cap element secured on one end of the nozzle member for mounting the nozzle member on a filler can, said cap element having a central aperture portion in communication with the interior of the nozzle member and defining at the intersection therewith a valve seat portion, said nozzle member including at the other end a lateral cutout portion extending through a side wall portion thereof, a reciprocable valve element seated on the valve seat portion for controlling communication between the filler can and the interior of the nozzle member, a valve actuating rod secured at one end to the valve element, the other end of said actuating rod terminating in a laterally extending end portion below the outer end of the nozzle member, said lateral end portion extending through and reciprocable in the lateral cutout portion in the side wall of the nozzle member and extending beyond the outer periphery of the nozzle member, abutment means extending laterally from longitudinally spaced portions of the inner periphery of the nozzle member and an intermediate portion of the actuating rod, and compression spring means interposed between the abutment means for urging the valve element into sealing engagement on the valve seat portion.

2. A nozzle assembly for filler cans comprising a tubular elongated nozzle member, a cap element secured on one end of the nozzle member for mounting the nozzle member on a filler can, said cap element having a central aperture portion in communication with the interior of the nozzle member and defining at the intersection therewith a valve seat portion, said nozzle member including at the other end a lateral cutout portion extending through a side wall portion thereof, a reciprocable valve element seated on the valve seat portion for controlling communication between the filler can and the interior of the nozzle member, a valve actuating rod secured at one end to the valve element, the other end of said actuating rod terminating in a laterally extending end portion below the outer end of the nozzle member, said lateral end portion extending through and reciprocable in the lateral cutout portion in the side wall of the nozzle

5 member and extending beyond the outer periphery of the nozzle member, abutment means extending laterally from longitudinally spaced portions of the inner periphery of the nozzle member and an intermediate portion of the actuating rod, compression spring means interposed between the abutment means for urging the valve element into sealing engagement on the valve seat portion, and a lateral notch portion extending through the side wall portion of the nozzle member for receiving the lateral end portion of the actuating rod therein, said notch portion being of a substantially lesser depth than the cutout portion.

10 3. A nozzle assembly for filler cans comprising a tubular elongated nozzle member, a cap element secured on one end of the nozzle member for mounting the nozzle member on a filler can, said cap element having a central aperture portion in communication with the interior of the nozzle member and defining at the intersection therewith a valve seat portion, said nozzle member including at the other end a lateral cutout portion extending through a side wall portion thereof, a reciprocable valve element seated on the valve seat portion for controlling communication between the filler can and the interior of the nozzle member, a valve actuating rod secured at one end to the valve element, the other end of said actuating rod terminating in a laterally extending end portion below the outer end of the nozzle member, said lateral end portion extending through and reciprocable in the lateral cutout portion in the side wall of the nozzle member and extending beyond the outer periphery of the nozzle member, abutment means extending laterally from longitudinally spaced portions of the inner periphery of the nozzle member and an intermediate portion of the actuating rod, compression spring means interposed between the abutment means for urging the valve element into sealing engagement on the valve seat portion, and a sealing washer disposed within the cap element, said sealing washer having a central aperture portion comprising a continuation of the valve seat portion for engagement around the outer periphery of the valve element, said valve element being comprised of a resilient sealing material and having a tapered end portion extending through the valve seat portion.
